UNITED STATES PATENT OFFICE.

ALPHONS H. GITS, OF CHICAGO, ILLINOIS.

OIL-CUP.

1,304,556.

Specification of Letters Patent. Patented May 27, 1919.

Application filed July 23, 1917. Serial No. 182,289.

To all whom it may concern:

Be it known that I, ALPHONS H. GITS, a citizen of the United States, residing at Chicago, in the county of Cook, State of Illinois, have invented certain new and useful Improvements in Oil-Cups; and I do hereby declare the following to be a full, clear, and exact description of the invention, such as will enable others skilled in the art 10 to which it appertains to make and use the same.

This invention relates to lubricating devices and is directed more particularly to oil cups.

15 The object of the invention is to obviate the necessity of forming the hinge ears of an oil cup integral with the consequent expense and at the same time to produce a structure that will have as great strength 20 as if the hinge ears had been formed integral. Thus the body of the cup, its lid and its applied hinged member may be each formed on a punch press with the well known economy.

25 In the drawings:—

Figure 1 is a side elevation of an oil cup constructed in accordance with the invention,

Fig. 2 is a vertical section therethrough, 30 Fig. 3 is a horizontal section taken on the line 3—3 of Fig. 1 with the closure cap removed,

Fig. 4 is a vertical section taken at right angles to Fig. 2, and

35 Fig. 5 is a disassembled perspective view of the cup.

Referring now more particularly to the accompanying drawing, there is shown generally at 5 an oil cup such as contemplated 40 by the invention, the same being capable of general application wherever the lubrication of the moving parts of machinery and the like is desired.

Specifically the cup 5 consists of a hollow 45 cylindrical body member 6 which is open at the top and is provided in its bottom with a discharge opening 7 communicating with a threaded nipple 8 carried by the body.

From its upper edge, the side wall of the 50 cup body 6 is cut-away or slotted inwardly as clearly shown in Fig. 5 to provide a recess 9 while inserted within said cup body is a substantially U-shaped member 10 that is preferably stamped from sheet material 55 on a punch press or the like and includes

spaced parallel ears 11 and a connecting bight portion 12.

The U-shaped member 10 is suitably inter-fitted with the side wall of the cup body, the ears 11 being slotted transversely as at 60 13 from their lower edges for substantially half their width and being so arranged as to extend outwardly through the recess 9 and beyond the side wall of the cup body. The slotted portions 13 of the ears 11 receive 65 and interlock with the side wall of the cup body at the base of the recess 9 whereby to procure the necessary strength and rigidity, while the connecting portion 12 of the member 10 contacts the side wall of the body 70 and completely closes the recess 9. Said connecting portion 12 is furthermore transversely bent arcuately as indicated at 14 in conformity with the curvature of the cup body and forms substantially a continuation 75 of the latter as will be readily seen in Fig. 3.

With the member 10 and body 5 assembled as above described they are suitably joined permanently by brazing or otherwise as desired.

80

The ears 11 are provided with transversely aligned perforations 15 and have engaged therethrough a pintle 16 while provided to normally cover the cup body is a closure cap 17 the same having formed 85 thereon integral ears 18 which straddle the ears 11 and are perforated to receive the pintle 16 whereby the cap is hingedly connected with the cup body. There is also provided a helical spring 19 which encircles 90 the pintle 16 between the ears 11 and has its ends respectively engaged with the cap and cup body so that the former is normally urged to close the body as will be clearly understood.

95

The lubricant is introduced into the cup body in the usual manner and as the operation of the cup is identical with that of the cups now universally in use, a description thereof is deemed unnecessary.

100.

What I claim is:—

1. An oil cup including a body having a recess in its upper edge portion, and a plate disposed against the inner wall of the cup in position to cover the recess and having terminal ears extending through the recess and constituting a medium for attachment of a cover for the body, the ears engaging against the outer face of the body.

105

2. An oil cup including a body, the wall 110

- of which is slotted downwardly from its upper end, a substantially U-shaped plate disposed within the body in position to cover the slot, said plate including spaced 5 ears and a connecting bight portion, the ears projecting outwardly through the slot and engaging over the bottom edge of the latter and constituting a medium for attachment of a cover.
- 10 3. The combination with a receptacle having an initial opening in its wall, of a plate disposed to close the opening, the plate being provided with an ear extending through the opening and beyond the outer wall of 15 the receptacle and constituting a medium for connection of a cover for the receptacle.
4. A cover-attaching medium for a receptacle including spaced ears and a connecting

bight portion, each ear at one side of its base being notched to receive a portion of 20 the wall of the receptacle.

5. An oil cup having a slot formed in its upper edge and a plate including spaced ears and a connecting bight portion, the plate being secured within the cup in position to close the opening and with the ears projecting outwardly through the opening, the lower sides of the ears being notched to receive the bottom edge of the slot.

In testimony whereof, I affix my signature 30 in the presence of two witnesses.

ALPHONS H. GITS.
